VELOCIPEDE

John A. Conti, Dothan, Ala., assignor to Hedstrom Union
Company, Fitchburg, Mass.

Filed Apr. 8, 1963, Ser. No. 74,341

Term of patent 7 years

(Cl. D34—15)

FIG. 3

FIG. 2 is a fragmentary enlarged rear perspective view thereof;

The dominant features of my design reside in the portions shown in full lines.

I claim:

The ornamental design for a velocipede, substantially as shown and described.
